UNITED STATES PATENT OFFICE.

HARRY C. FRICKE AND GEORGE E. TURNER, OF PITTSBURG, PENNSYLVANIA, ASSIGNORS TO TURNER-FRICKE MANUFACTURING COMPANY, OF PITTSBURG, PENNSYLVANIA, A CORPORATION OF PENNSYLVANIA.

EXPLOSIVE-ENGINE.

No. 864,143.

Specification of Letters Patent.

Patented Aug. 20, 1907.

Application filed March 19, 1907. Serial No. 363,235.

To all whom it may concern:

Be it known that we, HARRY C. FRICKE and GEORGE E. TURNER, citizens of the United States, residing at Pittsburg, in the county of Allegheny and State of Pennsylvania, have invented certain new and useful Improvements in Explosive-Engines; and we do hereby declare the following to be a full, clear, and exact description of the invention, such as will enable others skilled in the art to which it appertains to make 10 and use the same.

Our invention consists in the novel features herein-after described reference being had to the accompanying drawings which illustrate one form in which we have contemplated embodying our invention and said invention is fully disclosed in the following description 15 and claims.

In the operation of gas or explosive engines, particularly those having two or more cylinders, it is often desirable to throw out of operation the inlet valve, of one or more cylinders, as for example when the engine is to be started by means of compressed air applied to one or more cylinders, and also when it is desired to remove and replace an igniter plug while the engine is running, or for throwing out of operation one or more cylinders 20 of a multiple cylinder engine when running on a very light load, etc. Our invention consists in making the inlet valve operating rod or stem in two parts, which is in itself desirable as it enables the valve to be operated in a perfectly straight line, without any lateral strain, 25 or twist with respect to its seat, and we provide a movable guide for the upper end of the lower part of the valve operating rod, which can be moved and held in position so that the rod will not actuate the valve, and this mechanism for breaking the inlet valve stem or rod, 30 which is described in detail hereafter is preferably employed in conjunction with some means for opening the exhaust valve of the same cylinder and holding it open, to prevent compression or rarefaction in the cylinder, and thus relieve the other cylinders of the engine, 35 where there are several, from unnecessary load. We have shown herein one means for relieving the exhaust valve and holding it open, which can be advantageously employed, but the specific details of such relief mechanism we do not claim, and other forms of relief mechanism may be employed.

In the drawings, Figure 1 represents a vertical sectional view of a gas engine, of the multiple cylinder type, taken on a plane extending through a cylinder and the inlet and exhaust valves therefor, and showing 40 the mechanism for operating and controlling said valves. Fig. 2 is an enlarged sectional view of a portion of Fig. 1 showing the inlet valve and the mechanism for operating and controlling the same. Fig. 3 is a horizontal section on line 3-3 Fig. 2. Fig. 4 is a perspective view

showing various parts of the valve operating mechanism shown in Fig. 2, showing the parts separated. Fig. 4^a is a detail perspective view of a modified form of bracket for locking the valve operating rod guide in operative position. Fig. 5 is a view similar to Fig. 2 showing the valve operating mechanism in inoperative 55 position. Fig. 6 is an enlarged sectional view of part of Fig. 1 showing the exhaust valve and the mechanism for operating and controlling the same, the said valve being shown in open or inoperative position. Fig. 7 is a horizontal section on line 7-7 of Fig. 6. Fig. 8 is a 60 detail perspective view of the devices for throwing the exhaust valve into inoperative position, the parts being separated.

In the drawings A represents the engine base of an explosive engine which may have one, two or more 70 cylinders, only one of which shows in the sectional view Fig. 1.

B represents the cylinder, C the piston, D the piston rod, E the crank shaft; all of which may be of any preferred construction.

F represents the inlet passage for the explosive mixture and F' represents the inlet valve, fitting a seat f in said passage. The valve F' is provided with a stem f' passing through a suitable bearing and having a collar f² adjustably secured on its lower end, between 80 which and the bearing is a coiled spring f³, which keeps the valve F' normally seated.

Below the valve stem f' and normally in line therewith is the inlet valve operating rod, preferably formed in two parts f⁴, f⁵ adjustably connected. We prefer 85 to form the upper end of the part f⁵ with a threaded socket into which the lower end of the part f⁴ is adjustably screwed, and a jam nut holds the parts in their adjusted positions. The lower end of part f⁵ screws into a yoke f⁶ pivotally connected by a pin f⁷ 90 to a horizontal yoke on the end of an arm f⁸ which is pivoted to a stationary part of the base. The pin f⁷ also carries a friction roller which engages the inlet cam h on the inlet cam shaft H, said shaft being driven by gearing from the crank shaft at half the speed of the 95 crank shaft, as is usual in engines of the four cycle type.

The upper part f⁴ of the valve rod, extends through a bracket I, secured to the exterior of the cylinder, and provided with an aperture i of greater diameter than the rod f⁴, a second aperture i' of the same size, but 100 disposed angularly to the first aperture as shown best in Fig. 2, and a slot l connecting the apertures i and i', and of less diameter than said apertures but wide enough to permit the passage of the rod f⁴.

L represents a movable guide, or collar, having a 105 central bore fitting the rod f⁴, so as to permit the said rod to slide therethrough. The lower part of said guide or collar is turned as at l to fit either of the apertures

i or *i'* which we term locking apertures, and the upper part of the collar is enlarged to provide a shoulder *l'* and a milled portion *l*², to facilitate operating the device. In assembling the parts as shown in Figs. 1 and 5, the guide or collar *L* is slipped over the rod *f*⁴ and the locking portion *l* is dropped into the locking aperture *i* of bracket *I*, thereby holding the rod *f*⁴ exactly in line with the lower end of the valve stem *f'*. When the parts are in this relation and the engine is running, 10 it will be seen that the cam *h* will lift the rod *f*⁵, *f*⁶ and will thereby lift the valve *F'* from its seat at each rotation of the cam shaft *H*.

When it is desired to throw the cylinder out of operation for any purpose, it is only necessary to raise the 15 movable collar or guide *L* out of the locking aperture *i*, when the rod *f*⁴, *f*⁵ can be pulled forward, out of line with the valve stem *f'* as shown clearly in Fig. 5. The valve operating rod will remain in this position by gravity, but it may be positively locked, by 20 dropping the locking portion *l* of the collar *L* into locking aperture *i'* as shown in Fig. 5. The exterior locking aperture *i'* is not essential to the operation of the device, however, and might be omitted, in which case the bracket *I* would be shaped as shown in Fig. 25 4^a, the slot *i'* extending far enough to permit the rod *f*⁴ to disengage the valve stem.

When the valve operating rod *f*⁴ *f*⁵ is thrown out of operative position, the operation of the cam is not affected, and the cam will continue to operate the rod, 30 without affecting the inlet valve, so that when the rod is restored to its normal position the parts will be immediately restored to their working condition, and the inlet valve will be opened at the proper time in the cycle.

35 In connection with the mechanism above described, we prefer to provide means for holding the exhaust valve open, while the inlet valve remains seated, in order to relieve the suction or compression of the cylinder.

40 In the drawings we have shown one form of device which may be employed for this purpose, see Figs. 1, 6, 7 and 8.

G represents the exhaust passage for the cylinder *C*, and *G'* the exhaust valve engaging a seat *g*, and having a stem *g'* provided with a bearing, a collar *g*², and spring *g*³, for holding the valve normally on its seat, all substantially as described with reference to the inlet valve.

The exhaust valve is operated by a two part rod *g*⁴, 50 *g*⁵, adjustably united, the lower end of said rod being provided with a yoke *g*⁶, pivoted at *g*⁷ to a yoke on an arm *g*⁸, and carrying a friction roller *g*⁹, adapted to engage a cam *k* on the exhaust cam shaft *K*, connected by the usual gearing with the crank shaft. The part 55 *g*⁴ of the valve rod engages a stationary guide *I'* and the lower part *g*⁵ extends through a sleeve *M* secured to the engine base and provided with a spiral slot *m* (see Fig. 8). A rotatable hub *M'* is fitted over the sleeve *M*, and is provided with a set screw *m'*, the end 60 of which engages the spiral slot *m* in said sleeve, so that when the hub *M'* is turned, it will be raised or lowered. The hub *M'* is provided with an arm or handle *m*² and said hub is constructed to engage a shoulder on the rod *g*⁵ (formed in this instance by the socket *g*¹⁰) when the 65 hub *M'* is rotated in one direction, thus lifting the

valve *G'* off of its seat and raising it to the same or a greater height than that to which the cam normally raises said valve, thus disconnecting the cam and valve, and holding the exhaust valve open as long as is desired. By turning the hub *M'* in the opposite direction the valve rod *g*⁴ *g*⁵ will be lowered to bring the friction roll *g*⁹ into operative relation with the exhaust cam *k*.

70 What we claim and desire to secure by Letters Patent is:—

75 1. In an explosive engine, the combination with a cylinder having a passage communicating therewith, a valve for said passage, a valve actuating cam, valve operating mechanism, interposed between said cam and said valve, including a part held positively in fixed relation to said cam, but movable manually into and out of operative relation with said valve, and manually operated means for locking said part in operative relation with said valve for securing the continuous operation of said valve by said cam when desired, substantially as described.

80 2. In an explosive engine, the combination with a cylinder and an inlet valve for said cylinder, of an inlet valve operating cam, connections extending from said cam to said valve, including a rod having a pivotal connection at one end holding said rod in fixed relation with said cam but permitting its other end to swing out of operative relation with other parts of said connections, and means for locking said movable rod in operative position, substantially as described.

85 3. In an explosive engine, the combination with a cylinder, and an inlet valve for said cylinder, of an inlet valve operating cam, connections extending from said cam to said valve, including a rod, having a pivotal connection permitting it to swing out of operative relation with other parts of said connections, a movable guide for the free end of said rod, and means for locking said guide in position to hold said rod in operative position, substantially as described.

90 4. In an explosive engine, the combination with a cylinder, and an inlet valve for said cylinder, of an inlet valve operating cam, connections extending from said cam to said valve, including a rod, having a pivotal connection permitting it to swing out of operative relation with other parts of said connections, a guide for the free end of said rod movable in a direction longitudinally of said rod, and a part having a locking aperture to receive a portion of said guide, and hold said rod in operative position, substantially as described.

95 5. In an explosive engine, the combination with a cylinder, and an inlet valve for said cylinder, of an inlet valve operating cam, connections extending from said cam to said valve, including a rod, having a pivotal connection permitting it to swing out of operative relation with other parts of said connections, a guide for said rod movable in a direction longitudinally of said rod, and a locking device 100 having a locking aperture to receive a portion of said guide, and a slot extending from said locking aperture to permit said rod to move into inoperative position, substantially as described.

105 6. In an explosive engine, the combination with a cylinder, and an inlet valve for said cylinder, of an inlet valve operating cam, connections extending from said cam to said valve, including a rod, having a pivotal connection permitting it to swing out of operative relation with other parts of said connections, a guide for the free end of said rod movable in a direction longitudinally of said rod, a locking bracket provided with locking recesses, for receiving a part of the movable guide for holding the rod in operative and inoperative position, substantially as described.

110 7. In an explosive engine, the combination with a cylinder having an inlet passage and an inlet valve therefor provided with a stem, or a cam for operating said valve, a valve operating rod interposed between the cam and said valve, having a pivotal connection at one end holding said rod in fixed relation with said cam, but permitting its other end to be moved into and out of operative relation with said valve stem, and a locking device for holding the

non-pivoted end of said valve rod, in operative relation to said valve stem, substantially as described.

8. In an explosive engine, the combination with a valve provided with a valve stem, of a separate valve operating rod, normally located in line with the valve stem, and having a pivotal connection at its lower end, permitting it to move out of alignment with said stem, a vertically movable guide on said rod, provided with a locking portion, and a bracket having locking apertures to receive said locking

10 portion of the guide for holding said rod in operative and inoperative position, and a slot connecting said lock-

ing apertures, of less width than said apertures for permitting the passage of the rod from the operative to the inoperative position, substantially as described.

In testimony whereof we affix our signatures, in the 15 presence of two witnesses.

HARRY C. FRICKE.
GEORGE E. TURNER.
